UNITED STATES PATENT OFFICE.

PETER PEZUTO, OF PHILADELPHIA, PENNSYLVANIA.

DESIGN FOR A BALANCING TOY.

51,321.

Specification for Design.

Patented Oct. 2, 1917.

Application filed July 7, 1917. Serial No. 179,280. Term of patent 7 years.

To all whom it may concern:

Be it known that I, PETER PEZUTO, a citizen of the United States, residing at Philadelphia, in the county of Philadelphia and State of Pennsylvania, have invented a new, original, and ornamental Design for a Balancing Toy, of which the following is a specification, reference being had to the accompanying drawing, forming part thereof.

Figure 1 is a perspective view of my improved balancing toy; and

Fig. 2 is an enlarged plan view thereof.

I claim:

The ornamental design for a balancing toy as herein shown.

PETER PEZUTO.

Witnesses:

ARCHIE D. PEROLLA,
SILVIO GIARDINELLI.
